UNITED STATES PATENT OFFICE.

SAMUEL BERGSTEIN, OF MIDDLETOWN, OHIO, ASSIGNOR TO THE INTERSTATE FOLDING BOX COMPANY, OF MIDDLETOWN, OHIO.

PAPER BOX AND THE LIKE.

Application filed February 19, 1926. Serial No. 89,472.

This invention relates to improvements in paper boxes having particular reference to display boxes adapted to be adjusted at a suitable angle for displaying their contents.

5 The objects attained in the invention consist—first, in a box requiring the minimum amount of material and simply constructed thus making possible a low cost article; second, a display box on which the pedestal 10 and an advertisement card are neatly assembled as the box is filled and delivered to the customer; and third, a display box on which the pedestal for supporting the raised end of the box and the advertisement card 15 can be conveniently adjusted for arranging the box to display its contents.

The improved box as illustrated in the accompanying drawings and herein described is a modification of the box set forth 20 in my copending application for patent Serial #53,664, filed August 31st, 1925.

In the drawings:

Fig. 1 is a detail view illustrating the blank from which the body of the box is 25 formed;

Fig. 2 is a view illustrating the blanks for the advertisement card and the pedestal;

Fig. 3 is a view of the box closed;

Fig. 4 is a sectional view of the assembled 30 box, including the pedestal and advertising card as adjusted for displaying its contents.

As here shown, the body of the box is of symmetrical construction, the blank for making it, as illustrated in Fig. 1, consisting of a bottom portion 1, side portions 2, end portions 3, end sealing flaps 4—5, and side ornamental border flaps 6.

The blank for the pedestal consists of a top wall portion 7, end wall 8, end sealing flaps 9—10, side walls 11 and hinge flap 12, the side walls being free or floating on two edges as the pedestal is set-up.

The advertising card consists of the card portion 13, the hinge portion 14 and corner reinforcements 15.

In the preferred construction the sealing or glue flaps 5 of the blank for the body of the box, the flaps 9 and 12 of the pedestal and flaps 14—15 of the advertisement card 50 each have applied thereto a strip—a of adhesive tape which serves as the sealing element for assembling the box. While any suitable adhesive, as glue, cement, etc., are also suitable for use in the construction of the improved box, adhesive tape is a pre-

ferred material because of its cleanliness as applied to the box blanks, its quick response to the application of moisture in assembling the boxes, the relatively slight pressure required in forming the joints and the firmer adhesion between the sealing flaps, thus resulting in a box of better construction.

60 No novelty is claimed relative to the construction of the body of the box which represents common practice except as to the use of adhesive tape as the sealing element.

65 The novelty of the box consists in improved construction of the pedestal and the manner of attaching and adjusting the same relative to the body of the box. A feature 70 of improvement consists in the end wall construction of the pedestal which is designed to give special stiffness to the pedestal for better supporting the end of the box in display position. This is accomplished by a double-lap joint with a double application of the adhesive tape between the joints as 75 illustrated in the several figures of the drawings, being best shown in the sectional view in Fig. 3.

80 A second and more decisive improvement consists in the manner of assembling and adjusting the pedestal relative to the body of the box. To this end the top wall 7 of the pedestal is provided with the hinge flap 12, to which the adhesive is applied for securing the pedestal on the bottom of the box, the hinge joint 16 between portions 7 and 12 on which the pedestal turns being substantially flush with the lower cross edge of 85 the box. Thus the pedestal is free to turn on joint 16 and to be adjusted in the two relative positions illustrated in the drawings, namely, over the end and top and under the lid of the box as illustrated in Fig. 3 thus 90 effecting a very neat appearance as the box is closed, and under the box as illustrated in Fig. 4 to raise the end at a suitable angle 95 for displaying the contents of the box.

100 The display card is novel only in its relation to the pedestal both in the closed and open box, the arrangement being such that the display card will be folded neatly over the open top of the box, under the pedestal, as illustrated in Fig. 3, as the box is closed, and will extend in a generally vertical position free of the pedestal when the parts are adjusted for displaying the contents of the box. The corner reinforcing tabs 15 act 105 to stiffen the end of the box which is sup- 110

2
ported in raised position and also to hold the display card more firmly in position.

Having described my invention, I claim:

1. A display box including in combination with a body having an open top, a separate pedestal comprising a top, an end and opposite side walls free on bottom and rear edges, attached thereto, the top wall having a joining flap extension for securing the pedestal to the bottom of the box adjacent an end thereof, the pedestal being hinged at the rear of said extended portion and adjustable relative to said end over the top of the box as the box is closed and under said end as the box is opened to support the same at an angle for displaying its contents.
- 10 2. A display box including in combination

tion a body having an open top, a separate pedestal comprising a top, an end and opposite side walls, the end wall being formed 20 with an overlapping, adhesive joint fold along its lower edge, the top wall having a joining flap extension for securing the pedestal to the bottom of the box adjacent an end thereof, the pedestal being hinged at 25 the rear of said extended portion and adjustable relative to said end over the top of the box as the box is closed and under said end as the box is opened to support the same at an angle for displaying its contents. 30

In testimony whereof, I affix my signature.

SAMUEL BERGSTEIN.
